UNITED STATES PATENT OFFICE

1,955,179

ILLUMINATED SIGN

Harold J. Force, Niles Center, Ill.

Application March 9, 1932, Serial No. 597,731

11. Claims. (Cl. 40—130)

This invention relates in general to a caution, warning, directional or advertising display sign provided with means for rendering it more attractive or more easily seen or for illuminating it by natural or artificial light, and has more particular reference to a caution or warning sign which has a marginal rim, either plain or colored, made more visible by illuminating lights such as a flood light or an automobile head-light.

10 Among the objects of the invention are: to provide additional illumination for a caution, warning, directional or advertising display sign; to distinctively set off a directional or display sign by natural or artificial illumination; to provide means for attaching illuminating means to a sign or advertising display; to provide means for locking an illuminating display upon a sign or display; to attach a marginal illuminating rim or outline to a sign or display; to prevent the unauthorized removal of a marginal or outline illuminator; to produce an inexpensive metal holder for a running glass reflector; to produce a reflecting glass holder in which sections thereof may be slipped in place for easy repair and replacement; to provide a sheet metal holder which readily conforms to display signs of different shapes; to provide an inexpensive sheet metal holder which may be attached to wood and metal signs; and in general to produce the illuminating display holder for signs herein shown and described.

The accompanying drawing illustrates different forms of the invention, and in Fig. 1 is a view in elevation of a directional sign provided with a marginal reflector in accordance with this invention;

Fig. 2 is an enlarged detail view of one corner of the attaching means for a sign illuminator of this kind;

Fig. 3 is a sectional view taken on the line 3—3 of Fig. 1;

Fig. 4 is a modification of the angular or corner fastening;

Fig. 5 is a sectional view of a modified holder; and

Fig. 6 is a sectional view of a holder adapted for attachment to wood signs.

In illuminating caution, warning, directional or display signs for advertising and other purposes it is customary to employ plain and colored reflector buttons which outline the display letters, to utilize reflecting plates of metal or glass in which the words or characters to be made prominent are shown in relief or in outline.

55 The present invention provides for the further

distinctive illumination of a new sign or display or of an old one already erected or placed in position by applying thereto a marginal frame or an outline adapted to receive and hold an illuminating medium such as glass, either plain or colored and adapted to return or reflect natural or artificial light in such a manner that a person in front of the sign or display, or at a considerably wide angle of vision therefrom will receive the reflected or illuminated rays which make the display or sign more evident or more attractive, and in this way direct it to the attention of the observer, rendering more noticeable, for example, the approach of an automobile to a caution, warning, or directional sign placed along the roadside, and making more attractive a window or other display so that an observer will be attracted more readily thereto.

Referring now more particularly to the drawing, a standard stop sign 8 is shown in Fig. 1, 75 of a type commonly used for highway signs, often made of thin metal and having the surfaces enameled or otherwise covered and protected to resist wear and weather. These signs are relatively inconspicuous and usually have no means 30 of illuminating them nor of making them stand out brilliantly in the dark except the contrasting color of the directional indicators or letters 9. By applying to a sign of this kind a marginal, 85 sectional reflector consisting of running reflectors 10 and 11, it is possible to outline the sign with a distinctive margin which renders it conspicuous and glowing under the light rays from the headlights of an approaching vehicle so that the sign itself will be more apparent and the 90 direction which it bears will be more readily seen. The running reflectors 10 and 11 may have an enlarged outer rounded lens portion 12, as shown in Fig. 3, with a reduced neck 13 and a convex reflecting surface 14 provided with any suitable 95 reflecting coating such as a mirror or the like, or provided with a number of innumerable rounded depressions 15 which act as reflectors magnified by the outer running lens portion 12 and preferably covered by a reflecting medium such as a 100 silver or foil backing and protected by a plastic or other coating.

A holder for the running reflectors adapted to embrace the edge of a thin metal sign 8 is shown in Fig. 3 comprising a back portion 17 adapted 105 to extend along the edge of the sign with a bent portion 18 extending over the edge to the front of the sign and having a reverse bend 19 and a portion 20 abutting the front of the sign and a lower inwardly bent edge 21 to form a dovetailed chan- 110

nel into which the holder or neck portions of the reflector elements 10 and 11 are slidable. At the ends of each back portion 17 are perforated ears 22 adapting the various sections to be secured together at the angles or corners of the sign by fastening means such as screws or rivets 23. The ears may be formed out of the back portion itself or angular pieces 24 may be separately attached at the ends as shown in Fig. 2, to connect the holders at the corners.

10 Instead of the perforated ears, cooperating interlocking ears 25 and 26 may be provided, as shown in Fig. 4, it being customary to compress the interlocking edges when the illuminating 15 holders and elements are in place upon a sign to prevent their unnoticed removal.

20 A somewhat simpler form is shown in Fig. 5, in which a clip 27 extends over the opposite sides of the edge of a sign to which is attached a dove-tailed holder 28 by soldering, riveting, or spot 25 welds 29. In this holder is shown an illuminating member 30 having a base of a width to be received in the dove-tailed groove and an outer, rounded, continuous lens portion 31 with a reflecting back 32 of any desired form.

25 In order to attach a holder of this kind to a sign made of wood, the back leg 33 of a holder clip 34 is extended at right angles thereto and has a perforation through which a screw 35 or 30 other suitable fastening device may be inserted into the wood or frame 36 of the sign.

35 To attach reflecting elements to a sign or display at other points than about the marginal edge thereof, the back clip or holder may be omitted and the front or dove-tailed portion may be perforated and attached by screws or other 40 fastening means directly to the sign. The reflecting or illuminating means is then inserted in the dove-tailed groove which conceals the fastening means.

45 With these various constructions it is obvious that the reflecting and illuminating means are readily attached to the margin or edge, or to an outline in a sign, or they may be placed to constitute the sign itself; the holders may be attached together against unauthorized removal, and by making the illuminating means sectional, the parts thereof are easily replaced and removed should they become broken or need repair, or 50 should it be desired to change the colors of the reflectors themselves. Such holders are readily attached to signs already erected, either of metal or of wood, which will enable the signs already in use to be equipped the same as those which 55 may be supplied later with these reflecting members.

55 It is obvious that special contours of reflectors and holders may be provided, such for example, as the shield designs representing the United States through traffic route markers.

60 Various other changes and modifications may be made in the holders, and in the form of the reflecting members, without departing from the spirit and scope of the invention.

65 I claim:

1. The combination with a sign, of a holder adapted to engage the adjacent front and rear edges at the margin of the sign and comprising a dove-tailed holder and a reflecting medium

having a wide angle of reflection and adapted to slidably engage in the dove-tailed portion of the holder.

2. The combination with a sign, of a holder for the marginal edge of the sign adapted to engage over the front and rear faces thereof, means for securing angular holder sections together about the sign, a recessed supporting portion at the front of the holder, and a reflecting illuminating means movable in the recessed supporting portion.

3. A holder for sign reflectors comprising a sheet metal clip to fit over the opposite faces of a sign member, a grooved slide member attached to the clip and to extend along the margin of the sign on one side, and a reflecting member movable in the slide.

4. A marginal holder for sign reflectors, comprising a sheet metal clip section to fit over the edge of a sign, means for attaching adjacent sections together at the ends, and means for mounting a reflecting member in the clip at one side of the sign.

5. A marginal holder for sign reflectors comprising a sheet metal strip bent to engage over the opposite faces of a sign and having a dove-tailed portion on the exposed side of the sign extending along the margin thereof to receive a reflector.

6. A holder for sign reflectors comprising a metal strip bent to embrace opposite sides of a sign at the edge thereof and a dove-tailed section extending along the edge of the sign at one side thereof.

7. A holder according to claim 6 in which the dove-tailed section is formed as an integral part of the strip which is reversely bent upon itself at one side of the dove-tailed section.

8. A holder for sign reflectors for angular margins, comprising a holding strip to engage opposite faces of a sign and with a recessed front portion, the ends being angularly cut to fit closely together, and perforated fastening ears at the ends of the strips by which they are fastened together.

9. The combination with a marginal holder for signs, of a recessed member at the front, a sectional running reflector slidably into the recess, means for securing the end of the holder together and thus holding the reflector sections in place.

10. A reflector holder for signs comprising an angular holder to engage adjacent faces at the edge of a sign, a dove-tailed reflector support attached to one angular portion of the holder, and means for securing the other angular portion of the holder to a sign.

11. A metal strip holder for sign reflectors comprising a clip portion to fit over the edge of a thin metal sign and an attached portion on one face forming a receiving groove to extend along the edge of a sign, the ends of the holder being angularly cut to fit an angularly shaped sign, the ends of the holder having perforated projections at the rear, and fastening means inserted through the perforations of adjacent projections by which the holder is secured to a sign.

HAROLD J. FORCE.
